UNITED STATES PATENT OFFICE.

WILLIAM D. McCULLOUGH, OF DETROIT, MICHIGAN.

RIM CONSTRUCTION.

Application filed August 2, 1923. Serial No. 655,187.

This invention relates to improvements in spring cushion formations, pertaining more particularly to the part generally known as the rim structure employed in connection with such formations.

The cushions used in connection with automobiles are produced generally under large production capacity conditions, so that the formations are more or less of a stage 10 development during the process of fabrication, no attempt being made to select elements or structures to produce a completed structure having characteristics individual to itself—the structures of a common type 15 are designed to be substantial duplicates.

To produce this result it is, of course, necessary that the various features that enter into the complete formation are themselves substantial duplicates, but as in the case of 20 all production operations, there is more or less variation from a standard, and it is therefore essential that the parts be so arranged and formed as to meet the conditions brought about by these variations, and 25 at the same time provide that desired general uniformity in final product.

One of the essential elements employed in producing a formation of this type is the 30 part generally known as the rim strip, this being the border strip which practically forms the part of the formation that is seated on the vehicle seat or frame itself, this strip carrying bottom portions of the coil springs, and generally carrying either 35 the apron or the downwardly extending portion of the cushion, depending upon the particular type of cushion employed.

Not only are the conditions of production 40 important factors, in the characteristics of the rim strip; the conditions of service also play an important part in connection with the selection of the type of rim strip which may be employed. For instance, a rim strip that contacts with the body seat of the vehicle 45 only at an outer margin, tends to place a strain upon the strip in service since the pressure exerted on the inner portion of the strip by the weight of the rider compressing the spring, tends to twist or distort the strip itself, so that the latter must be formed 50 of a material of such weight and gage as would inherently resist this deforming action, the result being that the material must be of a comparatively heavy gage; in addition, any variation as by warping or bending 55 of the strip at such margin tends to

break down the length of contact and thus effects the stability of the structure in use.

Another characteristic is found in the 60 readiness with which the apron or the cushion structure may be secured to the rim strip. Because of the strength requirements, the rim strip is generally of a metal shell-like construction, it being a common practice 65 to enclose within this structure a tacking strip of fiber or other suitable material to which the apron or cushion can be secured by tacking, this type being generally employed. The fact that the tacking strip is 70 enclosed within the shell-like structure practically requires that the edges of the metal structure be brought over the outer face of the tacking strip in order to retain the latter within the structure—it being understood, of course, that the intermediate portion of the metal is provided with the spaced 75 projecting portions on the inner side of the tacking strip, the space between these projections receiving a part of a spring convolution, the projections being clamped over the 80 positioned convolution. Owing to the fact that the projecting portions which receive the spring are practically limited as to spacing by the gage of the spring material, it 85 becomes a somewhat difficult matter to enclose the tacking strip by the shell structure itself and at the same time leave a sufficient amount of the tacking strip exposed to permit of rapid tacking of the apron or cushion structure in position; it will be readily 90 understood that with a small exposure of the tacking strip, it becomes necessary for the trimmer to take considerable care in the placing of his tacks in order that the latter 95 will enter the tacking strip and not be driven on to the metal portion of the surface over which the apron extends.

To meet this condition it has been proposed to employ a cross section of rim strip in which the top and bottom faces are inclined in opposite directions so as to provide a greater width at the outer face of the rim strip, thus enabling a greater width of tacking strip face to be exposed for tacking purposes. This, however, brings in the 100 difficulty that the contact with the vehicle seat is practically limited to the outer margin of the rim strip, thus presenting the 105 difficulty heretofore pointed out.

These difficulties, together with others— 110 such for instance as the fact that the apron or cushion structure and the tacks overly the

outer face of the rim strip, so that they are constantly subject to wear when the cushion is being positioned on or removed from the seat—have led, in some cases to a different 5 type of strip formation by means of which tacking of the apron or cushion may be avoided; this, however, requires a different structural formation and a different method of securing the flexible apron or cushion portion in position, tending to slightly increase 10 the cost and decrease the rapidity of operation by the trimmer.

The present invention has for its object 15 the production of a rim strip of the tacking strip type referred to, the invention being such as to produce a structure which will avoid many of the difficulties present—including those above referred to—and at the same time provide a cross sectional configuration 20 such as will permit of production at practically no greater cost than the prior structures and with at least equal facility, the strip, at the same time, being of greater strength than the strips heretofore employed 25 while permitting of an easier and more rapid application into the complete formation product through the ability of the trimmer to work with less care in the tacking operation, thus increasing trimming production 30 in manufacture.

To these and other ends, therefore, the nature of which will be more readily understood as the invention is hereinafter disclosed, said invention consists in the improved 35 construction and combination of parts hereinafter more particularly described, illustrated in the accompanying drawings, and more particularly pointed out in the appended claims.

40 In the accompanying drawings, in which similar reference characters indicate similar parts in each of the views,

Figure 1 is a section taken through a portion 45 of a spring seat formation, the formation being shown as located in its service position.

Fig. 2 is a bottom plan view of a portion of the spring cushion formation of Fig. 1.

Fig. 3 is a fragmentary perspective view 50 of the rim strip and the apron or cushion portion tacked thereto, the view showing parts in section.

In the drawings, *a* indicates the spring 55 formation generally made up of a plurality of coil springs suitably connected to provide a spring unit, *b* designates the cushion, shown as provided with a binding *b'* and which may, if desired, be simply the usual apron, and *c* designates the border or rim strip, this strip being generally arranged to provide a border around the lower portion 60 of the spring zone, and having a cross sectional configuration such as will permit springs to be secured in position at its inner side, and a depending portion of the cushion 65

or apron at the outer side. These elements are generally combined to produce a seat structure adapted for use in automobiles, the seat being adapted to be supported by a suitable part of the automobile frame and which 70 is indicated generally at *d*. Of these parts, those indicated at *a*, *b*, *b'*, and *d*, may be of the general type, and variable as to structure, etc., to produce the different varieties 75 of seat construction in general use. The present invention pertains more particularly to the part *c*, and this will now be described more in detail.

As shown, the rim strip is made up of the metallic channel member 10 and the tacking 80 strip portion 11, the latter being of suitable material, such for instance as fiber. The strip is generally made in lengths and then bent to the proper shape to provide the desired contour for the border, the ends of the 85 strip then being joined together to complete the border and maintain it against distortion, the arrangement being such that the strip is generally of similar cross section throughout its length, so that a description 90 of the strip on a cross sectional plane will practically describe the strip itself.

As shown for instance in Fig. 3, the member 10 is provided with a flat face 10^a which forms the seating face for the entire 95 cushion structure, this face thus extending in a practically horizontal plane and being designed to rest upon the support *d* throughout substantially the width of the face; at points in the direction of length of the strip 100 itself, this condition is varied, as presently described, through the fact that in crimping the spring convolution in place, there may be a tendency to shift a portion of this particular face out of such plane. It will be 105 understood, of course, that in referring to a horizontal plane with respect to this face, the term is employed in a relative sense, it being readily understood that the plane may extend in other directions than horizontal, 110 where the installation is of a type such as to place this face in a different relation to the general structure with which the strip may be combined.

The face portion 10^a, as shown, leads into 115 a channeled portion 10^b, the channel being provided by two projecting portions, each of which is produced by doubling the metal upon itself. These projecting portions are more or less similar to those heretofore employed in the art, the principal difference 120 being that in the present construction, the lower portion of the lower projection extends as a part of face portion 10^a. In practice, a portion of a convolution of a spring 125 is inserted into the channel after which those portions of the projections which project on to the inside of the convolution, are crimped by a suitable tool, thus anchoring the spring convolution within the channel. 130

The projections and channel portion have heretofore been employed, but in prior structures it is generally the case that the upper run of the upper projection is continued in practically the same plane to the outer portion of the tacking strip; such structures, after the edges of the member have been turned over onto the tacking strip, provide but a very narrow exposed face of the tacking strip, due to the fact that the channel 10^b is of comparatively small dimensions. In the present invention this has been changed by providing a vertical continuation 10^c of the member to a suitable distance, after which the member is bent over to carry it outward, as at 10^d. In this form, the structure is practically a continuous channel of a width sufficient to receive the tacking strip 11. To complete the rim strip, the margins of member 10 are bent toward each other over the positioned tacking strip 11, thus securing the tacking strip in position.

Because of the vertical height of the member produced in this way, a tacking strip of considerable vertical height may be employed and the inturned margins of member 10 will overlie the tacking strip to such an extent as to prevent any possibility of the tacking strip being moved from its position, the tacking strip being practically anchored within member 10 by this arrangement. And although this anchoring action be present, the distance between the opposite inturned margins of member 10 is such as to provide for a considerable exposure of the tacking strip therebetween.

And this effect is enhanced by the fact that the thickness of the tacking strip at the bottom is in excess of that at the top, the arrangement thus causing portion 10^a to extend outwardly a greater distance than the upper portion, this being shown more clearly in Fig. 1 wherein the lower portion of the rim strip is shown as projecting a considerable distance beyond the upper portion of member 10, the complete configuration being such as to provide this lower marginal portion 10^e as bent inwardly at an angle; hence there is an extended surface contact between this margin portion 10^e, and the positioned tacking strip.

As shown in Figs. 1 and 3, the inturning of the margins of member 10, provided under heavy pressure, tends to compress the tacking strip and to force it into the spaces which form the doubled portions of the projections, so that the tacking strip is held very firmly in position within member 10.

If desired, and this is preferred, the exposed portion of the tacking strip may be curved outwardly as shown in Figs. 1 and 3, thus not only providing for a neat and attractive appearance, but also enabling the trimmer to provide a more finished product

when attaching the curtain portion b' or apron, as the case may be.

As shown in Fig. 1, the rim strip formation provides not only the advantages referred to, but also insures a flat and extended seating surface on part d, and at the same time meets another condition that is of importance in operation, as will be understood from the fact that it is the practice to employ an upstanding member d' to prevent the outward movement of the cushion seat in service, this member being generally of metal. Under the usual types of structures, the fact that the tacking strip projects outward to practically the outward plane of the rim strip places the depending portion of the cushion or the apron as the case may be, as projecting outside of the normal limits of the rim strip, so that any movement of the seat while in position tends to damage the curtain or apron, as well as the tacks, through contact with member d'; and when the seat is being placed in position or being removed, this tendency is always present, so that there is a continuous liability of damaging the connections as well as the appearance of the cushion depending portion or apron. In the present arrangement, this is avoided through the fact that the projecting bottom portion of the rim strip prevents contact of the cushion or apron with member d' either in service or during periods when the seat is being positioned or removed from the automobile.

The rim strip can be produced in a simple and efficient manner by the general methods heretofore employed in producing rim strips, so that the cost of production is not materially increased and, at the same time, the positive advantages heretofore pointed out, together with other obvious advantages, will be obtained.

While I have herein shown and described the preferred way in which the present invention may be carried into effect, it will be understood that changes and modifications therein may be found desirable or essential in meeting the exigencies of use, and I desire to be understood as reserving the right to make any and all such changes and modifications as may be essential in so far as the same may fall within the spirit or scope of the invention as expressed in the accompanying claims when broadly construed.

What I claim is:—

1. In upholstery spring construction, wherein the upholstery is supported by spiral springs and the upholstery includes a marginal portion positioned to curtain the spring formation, a rim strip assembly adapted to support a spring turn on a lateral face of the assembly and to position the lower margin of the upholstery marginal portion, the spring turn and the margin of

the upholstery material being secured on opposite sides of the assembly, said assembly comprising a shaped metallic strip and a tacking strip secured within the metallic strip by bent marginal portions of such metallic strip, a cross section of the assembly presenting such strip marginal portions as extending in generally opposite directions toward a medial horizontal plane of the assembly with the edges of such portions spaced from such plane to present an exposed tacking zone of the tacking strip, said marginal portions extending toward such horizontal plane in different directions relative to a vertical plane of the assembly through the tacking strip, the tacking strip having faces complementary to and in contact with said oppositely-extending marginal portions of the metallic strip throughout the cross-sectional width of such portions.

2. A rim strip assembly as in claim 1, characterized in that one of the strip marginal portions extends inwardly toward such vertical plane.

3. A rim strip assembly as in claim 1, characterized in that the strip marginal portion below the tacking zone extends inwardly toward such vertical plane.

4. A rim strip assembly as in claim 1, characterized in that the metallic strip portion which forms the bottom of the assembly extends in a horizontal plane and the marginal portion leading therefrom extends inwardly toward the vertical plane, whereby the assembly presents a portion projecting outwardly beyond the exposed face of the tacking strip and below the tacking zone.

5. A rim strip assembly, as in claim 1, characterized in that the marginal portion of the strip above the tacking zone extends approximately parallel to the vertical plane, the marginal portion below such zone extending inwardly toward such vertical plane.

6. A rim strip assembly as in claim 1, characterized in that the marginal portion of the strip above the tacking zone extends approximately parallel to the vertical plane, the marginal portion below such zone extending inwardly from beyond the outer plane of the upper marginal portion toward such vertical plane.

7. A rim strip assembly as in claim 1, characterized in that the marginal portion of the strip above the tacking zone extends approximately parallel to the vertical plane, the marginal portion below such zone extending inwardly from beyond the outer plane of the upper marginal portion toward such vertical plane, the amount of outward projection of the lower marginal portion being such as to locate the tacked portion of the upholstery marginal portion within the space included between such vertical plane and a plane parallel thereto and pass-

ing through the point of greatest projection 65 of the strip marginal portion below the tacking zone.

8. In upholstery spring construction, wherein the upholstery is supported by spiral springs and the upholstery includes a 70 marginal portion positioned to curtain the spring formation, a rim strip assembly adapted to support a spring turn and to position the lower margin of the upholstery 75 marginal portion, said assembly comprising a shaped metallic strip and a tacking strip secured within the metallic strip by bent marginal portions of such metallic strip; a cross-section of the assembly presenting such strip marginal portions as extending in generally opposite directions, toward a medial horizontal plane of the assembly with the edges of such strip marginal portions spaced from such plane to present an exposed tacking zone of the tacking strip between the 80 opposed edges, said metallic strip having an intermediate portion of its cross-section bent to form a channel formation to receive the spring turn with the channel on the opposite side of the tacking strip from such strip 85 marginal portions, the lower wall of the channel formation extending in the bottom plane of the assembly with such bottom plane parallel to the medial horizontal plane, said tacking strip having a vertical 90 dimension greater than the similar dimension of the channel formation, the transverse dimension of such tacking strip being different on the opposite sides of the tacking zone, with the greater dimension located below 95 such zone.

9. A rim strip as in claim 8, characterized in that the exposed face of the tacking zone of the tacking strip projects outwardly beyond the strip marginal edges. 100

10. A rim strip as in claim 8, characterized in that the exposed face of the tacking zone of the tacking strip is curved outwardly to project beyond the strip marginal edges.

11. A rim strip assembly as in claim 8, 110 characterized in that the intermediate portion of the tacking strip carries the tacking zone and has a transverse dimension greater than the upper portion of the tacking strip and less than the lower portion of such tacking strip.

12. A rim strip assembly as in claim 8, characterized in that the intermediate portion of the tacking strip carries the tacking zone and has a transverse dimension greater 115 than the upper portion of the tacking strip and less than the lower portion of such tacking strip, the exposed face of the tacking strip being curved outwardly to project beyond the metallic strip marginal edges. 120

In testimony whereof I affix my signature.

WILLIAM D. McCULLOUGH.
